Inventor

By his Attorney *John Morris*

UNITED STATES PATENT OFFICE.

ALBERT E. TEPFER, OF NEW YORK, N. Y.

DESIGN FOR A SOCKET-COVER.

48,842.

Specification for Design.

Patented Apr. 4, 1916.

Application filed December 15, 1915. Serial No. 67,067. Term of patent 7 years.

To all whom it may concern:

Be it known that I, ALBERT E. TEPFER, a citizen of the United States, residing at New York city, in the county and State of New York, have invented a new, original, and ornamental Design for a Socket-Cover, of which the following is a specification, reference being had to the accompanying drawing, forming part thereof.

Figure 1 is a plan view of a socket cover

showing my new design; and Fig. 2 is a side elevational view thereof.

I claim:—

The ornamental design for a socket cover, as shown.

ALBERT E. TEPFER.

Witnesses:

CLARICE FRANCK,

JUDITH PARDEE.
